Primary Examiner — Daniel Bui(74) *Attorney, Agent, or Firm* — Greenberg Traurig, LLP(57) **CLAIM**

The ornamental design for a modular electrical connector, as shown and described.

DESCRIPTION

FIG. 1 is a top, front perspective view of a modular electrical connector showing our new design;

FIG. 2 is a bottom, front perspective view thereof;

FIG. 3 is a front side elevational view thereof;

FIG. 4 is a rear side elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawing views represent unclaimed portions of the modular electrical connector only and form no part of the claimed design. The dash-dot line represents the boundary of the claimed design.
